ATTORNEY

UNITED STATES PATENT OFFICE.

ALBERT S. HILLS, OF HAYDENVILLE, MASSACHUSETTS.

DESIGN FOR A DOUBLE BATH-COCK BODY.

SPECIFICATION forming part of Design No. 31,599, dated October 3, 1899.

Application filed May 20, 1899. Serial No. 717,661. Term of patent 14 years.

To all whom it may concern:

Be it known that I, ALBERT S. HILLS, a citizen of the United States, residing at Haydenville, in the county of Hampshire and State of Massachusetts, have invented and produced a new and original Design for a Double Bath-Cock Body, of which the following is a specification, reference being had to the accompanying drawings, forming a part thereof.

Figure 1 is a plan view of a double bath-cock body, showing my design; and Fig. 2 is a front view of the same.

As shown in the drawings, the leading or

material features of my design consist of the inverted-U-shaped body, with the twin faucet extensions on said body arranged at angles to the parallel straight parts thereof.

Having described my invention, what I claim is—

The design for a double bath-cock body, as herein shown and described.

ALBERT S. HILLS.
